Archibald J. Turner, Chicago, Ill., assignor to Wilson Athletic Goods Mfg. Co., Inc., Chicago,
Ill., a corporation of Delaware

Application February 8, 1945, Serial No. 117,827

Term of patent 14 years

(Cl. D3—11)

To all whom it may concern:

Be it known that I, Archibald J. Turner, a citizen of the United States, residing in Chicago, in the county of Cook and State of Illinois, have invented a new, original, and ornamental Design for a Baseball Mitt, of which the following is a specification, reference being had to the accompanying drawing, forming part thereof.

Fig. 1 is a perspective front view of a baseball mitt embodying my new design; and

Fig. 2 is a perspective view of the rear of the baseball mitt shown in Fig. 1.

I claim:

The ornamental design for a baseball mitt, substantially as shown.

ARCHIBALD J. TURNER.
